UNITED STATES PATENT OFFICE.

JARED LOCKWOOD AND WILLIAM A. KEYS, OF NEW YORK, N. Y.

HOLDER FOR SCARFS, &c.

SPECIFICATION forming part of Letters Patent No. 285,281, dated September 18, 1883.

Application filed May 4, 1883. (No model.)

To all whom it may concern:

Be it known that we, JARED LOCKWOOD and WILLIAM A. KEYS, both of the city, county, and State of New York, have invented a new and useful Improvement in Holders for Scarfs and Cravats; and we do hereby declare the following to be a full, clear, and exact description of the same, reference being had to the accompanying sheet of drawings, forming part of this specification.

This invention is in the nature of an improvement in holders for scarfs and cravats; and the invention consists in a scarf or cravat holder constructed with a slot which is wider at the top than at the bottom.

The invention also consists in a scarf or cravat holder provided with prongs, whereby it may be attached to the cravat or scarf; and the invention still further consists in a cravat or scarf holder bent in **U** form, with a slot for the neck of the button in one side and an orifice in the other, all constructed in the manner and for the purpose hereinafter more fully described and claimed.

25 In the accompanying sheet of drawings, Figure 1 is a perspective view of a cravat with our holder attached thereto; Fig. 2, a cross-section of same; Fig. 3, a perspective view of holder detached; Fig. 4, a view of unbent holder attached to scarf; Fig. 5, a cross-section of same; Fig. 6, a perspective view of unbent holder.

Similar letters of reference indicate like parts in the several figures.

35 This invention has for its object the improvement of holders or devices fixed to scarfs or cravats for the purpose of keeping them snugly in place around the neck of the wearer. Heretofore such devices have been made with the slot designed to receive the neck of the button narrow at the top and wide at the bottom, which construction permits the button-head to slip through the slot, and renders the device less useful than it would otherwise be. 40 Therefore, in the construction of our holder, we form the slot A with its widest part *a* at the upper portion of the slot and its narrowest part *b* at the lower part of the slot. The holder is formed with suitable prongs, *c*, 45 extending backward and at right angles to it,

these prongs being sharpened, so that by simply inserting them through the stiff foundation B of the cravat or scarf and then bending over the prongs, as shown in Fig. 4, the holder is retained firmly in position and is 55 permanently fixed to the cravat.

To simplify the construction of these holders—that is, so that they may be readily stamped out by suitable dies from sheet metal or other material, and yet provide for the 60 projection of that part in which is formed the slot A—we make a holder, that the part D, in which is formed the slot A, and the part C, to which are fixed the prongs *c*, may be doubled in **U** shape, as shown in Figs. 1, 2, and 3. 65 This, it will be observed, permits the slot A to project out from the surface of the cravat or scarf, so that the collar-button can be received within the slot A. To provide for collar-buttons which are set with precious stones, 70 as is sometimes the case, we form in the part C of the holder an orifice, *e*, so that the stone will not be injured by chafing against the metal. It is to be understood that the holder hereinbefore described is secured to the inner 75 side of the scarf or cravat, so that it may engage with the collar-button, and when so engaged the cravat or scarf cannot move out of place either sidewise or below its proper position around the neck of the wearer. 80

When the prongs *c* are formed on the holder of the shape and construction shown in Figs. 4 and 5, one of these prongs, *f*, is located so as to afford the greatest resistance at the point of greatest strain. This last-named construction is shown in Figs. 4, 5, and 6.

Having now described our invention, what we claim as new, and desire to secure by Letters Patent, is—

A cravat-holder made with the parts C and 90 D bent in **U** form, the part D being provided with a button-receiving slot and the part C provided with the hole *e*, and means for attaching the holder to the cravat or scarf, substantially as shown and described.

JARED LOCKWOOD.
WILLIAM A. KEYS.
